US0D1058516S

(12) **United States Design Patent** (10) Patent No.: **US D1,058,516 S**
(45) Date of Patent: ** Jan. 21, 2025

(54) **USB OUTLET**

(71) Applicant: **Xiangyou Shen**, Sichuan (CN)
(72) Inventor: **Xiangyou Shen**, Sichuan (CN)
(*) Notice: Patent file contains an affidavit/declaration under 37 CFR 1.130(b).
(**) Term: **15 Years**
(21) Appl. No.: **29/951,800**
(22) Filed: **Jul. 11, 2024**

(51) LOC (15) Cl. 13-03
(52) U.S. Cl.
USPC **D13/147**

(58) **Field of Classification Search**

(57) **CLAIM**

The ornamental design for a USB outlet, as shown and described.

DESCRIPTION

FIG. 1 is a front, top perspective view of a USB outlet, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the USB outlet that form no part of the claimed design.

1 Claim, 8 Drawing Sheets
